GUN FIRING SYSTEM

Robert Carlin, Milwaukee, Craig W. Cannon, Waukesha, and Joseph M. Mather, West Allis, Wis., assignors to Allis-Chalmers Manufacturing Company, Milwaukee, Wis.

Application December 23, 1954, Serial No. 477,192

10 Claims. (Cl. 89—27)

This invention relates generally to gun firing systems and is more specifically concerned with a novel and improved apparatus for mechanically unlocking the firing pin or similar percussion mechanism located in the breech of a gun and thereby detonating the ammunition charge within the gun.

In gun firing mechanisms which utilize percussion to detonate the ammunition charge, it is necessary, in order to ignite the charge, that a sharp blow be struck upon the primer case of the cartridge. The mechanism which imparts this blow is located in the breech of the gun and usually consists of a firing pin, levers to withdraw the firing pin after it has struck, and a firing pin control mechanism or breech sear which releasably holds the firing pin in a retracted position. A spring is ordinarily used to drive the firing pin against the primer case, and the breech sear, which is actuated by a trigger device, holds the firing pin in a retracted position against the propelling force of the firing pin spring.

The trigger device used to actuate the breech sear in this type of firing mechanism should be capable of moving the breech sear practically instantaneously from the locking position holding the firing pin mechanism. This is desirable in order that the firing of the gun will take place at substantially the same instant that the operator of the gun actuates the trigger mechanism. In addition, if the breech sear is not moved out of engagement with the firing pin mechanism abruptly, faulty firing and excessive wear within the firing mechanism itself occurs due to the frictional engagement between the breech sear and the firing pin mechanism during the interval when the breech sear is only partially dislodged.

After the gun has been fired, and before the firing pin can be held in its cocked position in preparation for the next round, i. e., in its retracted position against the propelling force of the firing pin spring, it is necessary that the breech sear return to the original position it occupied before the firing pin mechanism was released. To return the breech sear to this position, gun firing mechanisms may provide a sear spring in the gun breech which yieldingly resists movement of the sear from its locking engagement with the firing pin mechanism. When a trigger mechanism for remote control of a breech sear is installed with a gun firing mechanism, because of the frictional losses within the trigger mechanism, the apparatus used to return the breech sear to its prefiring position is often insufficient to return the breech sear against the frictional drag of the trigger mechanism. When this situation occurs it is necessary to modify considerably the gun breech firing mechanism when a remote control trigger mechanism is installed, to insure that the breech sear will properly return to its prefiring position. This frictional resistance of the trigger mechanism becomes increasingly important as the distance between the trigger mechanism and the gun breech is increased.

Generally, it is an object of this invention to provide an improved system for remotely controlling the firing of guns, and which system lends itself for use in connection

2

with gun firing mechanisms of the hereinbefore outlined character.

More specifically, it is an object of this invention to provide an improved gun firing system which will impart sequentially a firing stroke and a return stroke to a firing pin control mechanism in a gun breech.

Another object of this invention is to provide an improved gun firing system which employs a spring powered power transmitting means to impart sequentially to a firing pin control mechanism a firing stroke and a return stroke.

Still another object of this invention is to provide a gun firing system of the hereinbefore described character which employs a spring powered actuating element to impart to a trigger control element actuating the firing pin control mechanism in a gun breech, a firing stroke and a return stroke, wherein the actuating element cannot be cocked until the trigger control element has completed its return stroke.

20 A further object of this invention is to provide a gun firing system of the hereinbefore outlined character wherein the firing stroke imparted to the firing pin control mechanism can be readily adjusted by adjustment within the gun firing mechanism.

25 Quite frequently under modern conditions, it is desirable that several weapons which are stationed at different points be under the control of a single firing lever. In that case it is desirable, for practical operation, that the operator of the firing control unit be able to select 30 at will the number and combination of guns which he wishes to fire at any given time. Also, the firing control unit which is designed for multiple gun operation should be as small as possible, particularly so when used in a combat vehicle where space is limited.

35 Accordingly, it is still another object of this invention to provide an improved gun firing control system which can fire by the operation of a single control lever simultaneously any preselected combination of guns controlled by the system.

40 And still a further object of this invention is to provide a multiple gun control mechanism of the hereinbefore described character which forms a compact unitary structure, and which can readily be adapted for use with any desired number of guns in a multiple gun installation.

45 The foregoing and other objects and advantages are attained by the present invention, various novel features of which will become apparent as the following specification is read in conjunction with the accompanying drawings:

50 Fig. 1 is a side view of a gun firing control unit showing one of the gun trigger actuating mechanisms in the unit in an uncocked position and with parts of the front cover plate for the unit removed;

55 Fig. 2 is a front view of a multiple gun firing control unit having six individual gun trigger actuating mechanisms of the type shown in Fig. 1; part of the unit shown in Fig. 2 being shown in section along the line II—II of Fig. 1 to expose details of one of the trigger actuating mechanisms, and parts of the front cover plate being omitted to show a front view of another one of the mechanisms;

60 Fig. 3 is a sectional view of the gun trigger actuating mechanism shown in Fig. 1, Fig. 3 being drawn at a reduced scale and showing the mechanism in an uncocked position with front and rear cover plates, parts of the housing, and parts of a coupling mechanism omitted;

65 Fig. 4 is an other sectional view, at a reduced scale, of the mechanism shown in Fig. 1 and illustrating a temporary condition of the mechanism during the cocking operation;

70 Fig. 5 is a sectional view similar to Fig. 3 but showing the mechanism in a cocked position;

Fig. 6 is another view similar to Fig. 3 and illustrating a temporary condition of the mechanism during the operating cycle; and

Fig. 7 is another view of the mechanism illustrating a temporary condition during the operation cycle.

Referring to Figs. 1 and 2, a control unit 1 comprises six gun trigger actuating mechanisms 2 which are mounted side by side in a control unit housing 9. A firing cable 11 is connected to each trigger actuating mechanism 2 and leads from the top of the housing 9 to six firing mechanisms (not shown) located, respectively, in the breeches of six separate guns. As the gun breech firing mechanism forms no part of this invention, for the purposes of this disclosure it is enough to say that firing cable 11 will impart a firing stroke and a return stroke to a suitable firing control element (not shown) within the corresponding gun breech. This is done by sequentially imparting to any selected firing cable 11 a pull toward and a thrust away from the control unit housing 9, in the manner to be described.

The gun control unit housing 9 is formed by a frame type structure having three vertically spaced wall portions, namely upper horizontal wall 21, center horizontal wall 22 and lower tilted wall 23 which extend longitudinally of the control unit. Integrally formed with and connecting these three wall portions with each other are left and right vertical supporting walls 24 and 26, respectively. The control unit housing 9 is rigidly supported as by bolts 7 on a suitable bracket structure 8 so as to be within easy access of a gun control operator.

Detachably secured about the outside of housing 9 are three cover plates, namely top cover plate 27, rear cover plate 28 and front cover plate 29. These cover plates together with left and right supporting walls 24 and 26 enclose the six gun trigger actuating mechanisms and protect the mechanisms from dirt, moisture and dust which may be present about the control unit.

As can be seen in Fig. 2, extending between and fixedly secured to supporting walls 24 and 26 below center wall 22 is a main support shaft 31. Above support shaft 31 and between upper wall 21 and center wall 22 is a salvo shaft 32 rotatably mounted in supporting walls 24 and 26. These two shafts together with center wall 22 of housing 9 support the main operating components of the six gun trigger mechanisms in the gun control unit. As the gun trigger mechanisms are substantially identical, only one of them will be described.

Each of the gun trigger mechanisms is equipped with a forked cocking handle or lever 36 having two arms 37 and 38, and pivotally mounted at its bifurcated end about main support shaft 31. Rotatably mounted about a bearing sleeve 39 surrounding the main support shaft 31 between arms 37 and 38 of lever 36 are two identical actuating plates 41 and 42. These plates are positioned at opposite sides of a central control element or plate 43 rotatably supported between the actuating plates on bearing sleeve 39. Actuating plates 41 and 42 are joined at their outer periphery by two interconnecting pins 44 (Fig. 1) and 46 extending through both plates. From the foregoing it is apparent that plates 41 and 42, and pins 44 and 46 form a single actuating element which will rotate as a unit about shaft 31. Two small coil springs 47 and 48 (Fig. 2) are anchored in the inside lateral surfaces of arms 37 and 38 of cocking lever 36, and in the outside lateral surfaces of actuating plates 41 and 42, respectively. The springs 47 and 48 serve to position the elements described within the bifurcated end of forked cocking lever 36 and to exert a clockwise bias, as viewed in Fig. 1, on cocking lever 36 with respect to the actuating element 41, 42.

As can best be seen in Fig. 3, above the actuating plate assembly 41, 42 and seated in a recessed portion 51 of central housing wall 22 is a heavy coil compression spring 52. Extending axially through the coil spring 52 and pivotally secured to pin 44 of the actuating plate

assembly 41, 42 is a pull rod 53. Pull rod 53 has integrally formed at its lower end a flange portion 54 which bears against the lower side of center housing wall 22 to limit the upward movement of the pull rod. Adjustably secured to the upper end of rod 53 is a nut and washer assembly 56 which holds coil spring 53 under compression and seated within recess 51. The foregoing described structure forms a resilient means for constantly urging the actuating plate assembly 41, 42 to its limit position in a clockwise direction, which is reached when flange portion 54 strikes the lower surface of center housing wall 22.

As can be seen in Figs. 2 and 3, fitted into the lower front part of middle housing wall 22 and lying longitudinally along the lower surface of the wall above the actuating element 41, 42 and control element 43 is a sear mount 61. Extending along the back edge of sear mount 61 is a flange 62, and the mount is secured to the underside of wall 22 by means of a screw 63 protruding through flange 62 into wall 22. Directly above the control element 43 and extending transversely across sear mount 61 is a slot 64 permitting control element 43 to rotate beneath sear mount 61. Control element 43 is formed with an arcuate edge portion 66 concentric with its axis of rotation or pivot axis about support shaft 31. To the right of edge portion 66, as seen in Figs. 3 and 6, and in the outer edge of control element 43 is a notch forming two shoulders 67 and 68. The arcuate, downwardly facing inner surface of slot 64 in sear mount 61 is radially spaced farther away from the center of shaft 31 than the radially outer surface of arcuate edge portion 66. However, as shown in Fig. 3, shoulder 68 of control element 43 extends radially beyond the arcuate inner surface of slot 64. Consequently, control element 43 is free to rotate in a counterclockwise direction from the position in which it is shown in Fig. 6 to the position in which it is shown in Fig. 3, that is, until it reaches the limit position which is determined by shoulder 68 striking sear mount 61.

Referring to Figs. 2 and 4, pivotally secured by a pin 69 to a radially protruding portion 71 of control element 43 is a cable yoke 72. Cable yoke 72 is adjustably connected by nut and screw 73 to the firing cable 11 which extends outwardly through a cable conduit 74 to an associated gun firing mechanism as previously described. A control element return spring or auxiliary resilient means 76 is fixed to one end of pin 69 and to the under side of upper housing wall 21 so as to exert a tensile force on control element 43 and constantly urge the latter in a counterclockwise direction toward the limit position which is determined by shoulder 68 striking sear mount 61.

As shown in Fig. 3, control element 43 has formed at its lower edge a notch 77. Pivotally mounted about pin 46 between actuating plates 41 and 42 of the actuating element is an arm or pawl 78 for releasable locking engagement with notch 77. A retaining cup 79 fixed between actuating plates 41 and 42 forms a seat for a small coil spring 81 which is under compression and has its upper end in a spring seat portion 82 of pawl 78. Since spring 81 is under compression, pawl 78 is constantly being urged in a clockwise direction about pin 46.

Rotatably supported in sear mount 61 and extending longitudinally through the mount in overlying relation to the control element 43 is a sear assembly 86 (Fig. 7). As can be seen in Figs. 2 and 7, this assembly consists of three sear arms 87, 88 and 89 which are integrally united and rigidly secured to a cylindrical stem 91. Sear arm 87 lies in a common vertical plane with arm 37 of cocking lever 36, whereas sear arms 88 and 89 lie laterally of this plane between sear arm 87 and control element 43.

Extending transversely across sear stem 91 in a common vertical plane with control element 43 is a notch 92. When the sear assembly is rotated so that the sear stem

91 is in the position shown in Fig. 6, the arcuate inside surface of notch 92 will be radially spaced farther away from the pivot axis of control element 43 than the radially outer surface of the arcuate edge portion 66 of control element 43. Control element 43 may then freely rotate in a clockwise direction from the counterclockwise limit position shown in Fig. 3. With the control element 43 in the position shown in Fig. 3, rotation of the sear assembly to the position shown in Fig. 3 will thrust the inner edge of notch 92 in stem 91 below shoulder 67 of control element 43, and prevent rotation of the control element in a clockwise direction as viewed in Fig. 3.

Mounted on the lower wall 23 of the control unit housing 9 and in generally the same vertical plane as the control plate 43 is an adjustable stop comprising a striker screw 96 which is threaded into a tapped hole within the wall 23 and lockable in any position of axial adjustment by means of a jam nut 97. Adjustment of screw 96 in one axial direction or the other effects the operation of pawl 78 in a manner which will be more fully explained hereinbelow.

The mode of operation of the described gun firing control unit is as follows: In an uncocked position as shown in Fig. 3, compression spring 52 urges nut and washer assembly 56 and pull rod 53 upwardly within the housing so that flange portion 54 of rod 53 bears against the lower side of the middle housing wall 22. The actuating plate assembly 41, 42 will be in the position in which it is shown in Fig. 3 and which is its limit position for clockwise rotation. With the actuating plate assembly in this position, adjustable stop screw 96 has struck pawl 78 and pivoted it about connecting pin 46 against the force of coil spring 81 freeing pawl 78 from notch 77 in control element 43. The control element 43 is constantly being urged in a counterclockwise direction by control element return spring 76 to its limit position determined by shoulder 68 striking sear mount 61. In the uncocked position, sear stem 91 has rotated so that the inner edge of notch 92 in the sear stem is below shoulder 67 of the control element 43.

To cock the trigger actuating mechanism, the actuating plate assembly 41, 42 is rotated in a counterclockwise direction about central shaft 31. This rotation of the actuating plate assembly will force pull rod 53 and nut and washer assembly 56 downwardly so as to further compress compression spring 52. As the actuating plate assembly 41, 42 is rotated, coil spring 81 bears against spring seat 82 of pawl 78 rotating pawl 78 about pin 46 so that the pawl will contact and follow the outer peripheral edge of control element 43. When rotation is continued until the position shown in Fig. 5 has been reached, pawl 78 will drop into notch 77 of the control element. Since coil spring 52 is considerably stronger than return spring 76, coil spring 52 will now tend to urge both the actuating element 41, 42 and the control element 43 in a clockwise direction. However, since the inner edge of notch 92 in sear stem 91 is below shoulder 67 of the control element 43, the parts will be locked in their cocked position as shown in Fig. 5.

When it is desired to release the assembly, sear stem 91 is rotated so that the edge of notch 92 is raised above shoulder 67 and arcuate edge portion 66 is free to rotate past notch 92. The entire assembly now rotates in a clockwise direction under the force of coil spring 52, imparting a firing stroke to control element 43. Clockwise rotation of the actuating element 41, 42 and control element 43 in unison with each other from the cocked position shown in Fig. 5 continues until pawl 78 strikes the protruding end of screw 96. As the actuating element 41, 42 continues to rotate, pawl 78 will pivot about connecting pin 46 and release control element 43 from the torque of the actuating element 41, 42 as shown in Fig. 6. The actuating element 41, 42 will continue to rotate in a clockwise direction until flange 54 of pull rod 53

strikes the lower side of center housing wall 22. Since the control element 43 has been freed from rotation with the actuating element 41, 42, return spring 76 will impart a return stroke to control element 43 by rotating the element in a counterclockwise direction until shoulder 68 strikes sear mount 61, as shown in Fig. 3.

From the foregoing it will be apparent that coil spring 52, control element return spring 76, actuating element 41, 42 and pawl 78 constitute a spring biased power transmitting means which will impart sequentially to control element 43 rotation first in a clockwise direction to impart a firing stroke and then in a counterclockwise direction to impart a return stroke. This rotation occurs each time the actuating element 41, 42 rotates from its cocked to its uncocked position. The releasable coupling mechanism afforded by pawl 78 and notch 77 allows return spring 76 to rotate control element 43 in a direction opposite to that imparted to the control element 43 by the actuating element 41, 42, after the actuating element has completed a certain fraction of its rotation from its cocked to its uncocked position. Accordingly, firing cable 11 connected to the control element 43 is first pulled toward and then thrust away from the control unit housing 9. Adjustment of screw 96 will determine the instant at which, during the rotation of the actuating element from its cocked to its uncocked position, the pawl 78 will be tripped by screw 96 and disengaged from notch 77.

For cocking the individual trigger mechanisms it will be seen with reference to Fig. 7 that arm 37 of cocking lever 36 has formed at its inside edge a nub portion 101. Pin 44 connecting actuating plates 41 and 42 extends beyond plate 42 into the path of arcuate movement of nub portion 101 about the axis of shaft 31. When the cocking lever 36 is rotated in a counterclockwise direction from the position in which it is shown in Fig. 7, nub portion 101 will strike pin 44 and cause the actuating plates 41 and 42 to rotate about shaft 31 and thereby cock the mechanism. As previously explained, since coil springs 47 and 48 (Fig. 2) tend to rotate the cocking lever in a clockwise direction, as viewed in Fig. 7, with respect to the actuating element 41, 42, when the cocking lever is released after the trigger mechanism has been cocked, these springs will return the lever to its rest position against a stop abutment 102 formed in the lower housing wall 23, as shown in Figs. 5 and 7.

Referring to Figs. 2 and 7, it will also be seen that the upper end of arm 37 has integrally formed therewith an arcuate finger portion 104. When the sear assembly is in the position shown in Fig. 6, i. e., when the arcuate edge portion 66 of control element 43 lies beneath the arcuate inside surface of notch 92 of the sear stem, arm 87 of the sear assembly extends upwardly as in Fig. 7 in abutting relation to the forward end of finger 104. As a result, the sear assembly cannot be rotated from the position shown in Fig. 6 to the position shown in Fig. 4 because, as shown in Fig. 6, the inside surface of notch 92 will immediately strike arcuate edge 66, when finger portion 104, as shown in Fig. 7, strikes sear arm 87 and tends to rotate the sear assembly. Cocking of the trigger mechanism cannot be accomplished, therefore, until the control element 43 returns to its prefiring position shown in Fig. 3, which clears the edge of notch 92 for rotation below shoulder 67 in the control element 43. A sear spring 106 is fastened to arm 89 of the sear assembly and to the upper housing wall 21, respectively, to rotate the sear assembly into locking engagement with the control element after it has returned to its prefiring position.

One of the advantages of the present invention is that it is relatively easy to adapt it for use with any number of desired guns. A common firing device has been provided so that when any number or combination of gun trigger mechanisms have been cocked, they will be fired simultaneously by the actuation of a single control lever.

Referring to Figs. 1 and 2, secured to salvo shaft 32 by

means of hub sleeves 111 and brackets 112 is an actuating rod 113 which extends the length of the housing underneath the salvo shaft 32 in overlying parallel relation to support shaft 31. When the six gun trigger mechanisms 2 are axially aligned along the support shaft 31 as shown in Fig. 2, and return springs 76 have returned all control elements 43 to their prefiring positions corresponding to Fig. 3, sear springs 106 will rotate the sear assemblies of all trigger mechanisms until rotation is prevented by reason of sear arms 88 striking actuating rod 113. In this position, sear stem 91 of each sear assembly has rotated so that the inner edge of notch 92 in the stem is below shoulder 67 of the control element. Any or all trigger mechanisms may now be cocked as previously described and shown in Fig. 4, since the finger 104 of the respective cocking lever is free to pass over the sear arm 87 of the associated sear assembly, and the edge of notch 92 in the sear stem of each trigger mechanism will prevent clockwise movement of the respective control elements 43 from its prefiring position corresponding to Fig. 3. When salvo shaft 32 is rotated in a counterclockwise direction, as viewed in Fig. 1, actuating rod 113 moves to the right and rotates all sear arms 88 and associated sear stems 91 in clockwise direction with the result that the control element 43 of each mechanism will be released for rotation in a clockwise direction.

Any suitable means may be used for rotating salvo shaft 32 in the manner described. In the embodiment shown in Figs. 1 and 2, an arm 116 is secured to the end of shaft 32 which extends outwardly from left vertical supporting wall 24. At the free end of arm 116 a screw 117 and a clamping bracket 118 are provided to secure a salvo cable 119 to the arm 116. Salvo cable 119 is secured at its other end to any suitable control lever (not shown) so that movement of the control lever will be transmitted to the salvo cable 119 so as to rotate salvo shaft 32 in a counterclockwise direction as viewed in Fig. 1.

From the foregoing it will be seen that a simple and compact control unit has been provided which enables a gun operator to fire from a remote position any number or combination of guns connected to the control unit. Only those guns will be fired whose trigger mechanisms in unit 1 have been cocked. If a trigger mechanism is not cocked, movement of the actuating rod 113 and the sear assembly for the uncocked mechanism will not fire the gun associated therewith, since coil spring 52 and actuating element 41, 42 of the uncocked mechanism are not engaged with control element 43. The control element 43 of the uncocked mechanism will remain urged by return spring 76 to its limit position as shown in Fig. 3, in which shoulder 68 bears against sear mount 61.

Accidental firing is also effectively guarded against. Should the control element 43 fail to return completely to its prefiring position, rotation of the cocking lever 36 and actuating element 41, 42 to a position where pawl 78 engages notch 77 of the control element, and subsequent release of the cocking lever, would inadvertently impart to the control element 43 a firing stroke when the cocking lever is suddenly released. This action would occur since if the control element 43 had not completely returned, the inner edge of notch 92 in sear stem 91 would not have dropped below shoulder 67 of the control element 43, and the control element would be free to rotate in a clockwise direction with the actuating element 41, 42 upon the release of the cocking lever. By the provision of arcuate edge portion 66 in the control element and the complementary notch surface 92 in the sear stem, the trigger mechanism has been guarded so that it cannot be cocked until the control element has returned to its prefiring position. If the control element has not returned, the cocking lever 36 cannot be rotated since finger 104 of the cocking lever will strike arm 87 of the sear assembly and force the inside surface of notch 92 in the sear stem against arcuate edge portion 66. Also, if for any reason the control element 43 has returned to its prefiring position, but

the sear assembly has not returned so that it has not engaged shoulder 67 of the control element 43, finger 104 will rotate the sear assembly by movement of arm 87, and the edge of notch 92 of the sear assembly will be moved into engagement with shoulder 67 of the control element before the mechanism is cocked.

Should the gun control operator decide not to fire a particular gun after he has cocked the trigger mechanism associated with the particular gun, he is able to manually 10 uncock the trigger mechanism without firing the gun. This can be done by rotating the cocking lever 36 and actuating element 41, 42 in a counterclockwise direction until pawl 78 is free of notch 77 in the control element 43. The lower end of pawl 78 is then swung manually in a 15 direction so as to pivot about pin 46 against the pressure of spring 31. While keeping the pawl released, the cocking lever, pawl and actuating element 41, 42 can then be eased back against the pressure of spring 52 to an uncocked position.

20 The firing stroke and the return stroke imparted to the control element 43 and the firing cable 11 can easily be adjusted by adjusting the trip means including screw 96 whereby the control element 43 is released from rotation with the actuating element 41, 42. If screw 96 is adjusted 25 so as to trip pawl 78 from notch 77 in the control element 43 after the actuating element 41, 42 has completed considerably less than its total arcuate travel from the cocked to the uncocked position, a relatively small firing stroke will be imparted to control element 43. On the other hand, if screw 96 is adjusted to trip pawl 78 after 30 the actuating element 41, 42 has completed substantially all of its arcuate travel from the cocked to the uncocked position, the firing stroke imparted to the control element 43 will be relatively large.

35 While I have described only one particular embodiment of my invention, it should be understood that I do not wish to be restricted thereto and that I intend to cover all modifications of the invention which would be apparent to one skilled in the art and that come within 40 the scope of the appended claims.

It is claimed and desired to secure by Letters Patent:

1. In a gun firing system, the combination of a support, a gun trigger control element pivotally mounted on said support, a releasable coupling mechanism including an actuating element rotatably mounted on said support and cooperable with said control element so as to impart a firing stroke to the latter by rotation of said actuating element from a cocked to an uncocked position, resilient means operatively interposed between said support and actuating element so as to be tensioned by rotation of said actuating element from said uncocked to said cocked position, a sear element adjustably mounted on said support for movement into and out of locking engagement with said control element while the latter is in a starting position for said firing stroke, trip means cooperable with said coupling mechanism so as to disconnect said actuating element from said control element upon movement of said actuating element from said cocked toward said uncocked position, and auxiliary resilient means operatively connected with said control element so as to urge the latter toward said starting position.

2. The combination set forth in claim 1, wherein said releasable coupling mechanism comprises a pawl element swingably mounted on one of said control and actuating elements and lockingly engageable with the other upon rotation of said actuating element into said cocked position.

3. The combination set forth in claim 1, wherein said releasable coupling mechanism comprises a pawl element swingably mounted on said actuating element and lockingly engageable with said control element upon rotation of said actuating element into said cocked position, and wherein said trip means comprise an arm on said pawl and a stop mounted on said support so as to be struck 70 75

by said arm upon movement of said actuating element from said cocked toward said uncocked position.

4. The combination set forth in claim 3, wherein said stop comprises a striker element engageable with said arm, and means mounting said striker element on said support for back and forth adjustment generally in the direction in which said arm moves about the pivot center of said control element during said movement of said actuating element from said cocked toward said uncocked position.

5. In a gun firing system, the combination of a support, a gun trigger control element pivotally mounted on said support and having an arcuate edge portion concentric with its pivot axis, spring biased power transmitting means including a releasable, automatically controlled coupling mechanism operatively interposed between said support and said control element for sequentially imparting a firing stroke and a return stroke in rotatively opposite directions to said control element, a sear adjustably mounted on said support in cooperative relation with said control element so as to prevent a firing stroke of the latter as long as said sear is in a locking position and so that upon adjustment of said sear to an unlocking position and a subsequent firing stroke of said control element said arcuate edge portion of the latter will cooperate with said sear to prevent return of the latter to its locking position until said return stroke has been imparted to said control element.

6. In a gun firing system, the combination of a support, a gun trigger control element pivotally mounted on said support and having an arcuate edge portion concentric with its pivot axis, means including a spring biased actuating element pivotally mounted on said support and an automatically controlled releasable coupling mechanism operatively interposed between said actuating and control elements for sequentially imparting a firing stroke and a return stroke to said control element in rotatively opposite directions, and a sear rotatably mounted on said support for selective adjustment to locking and unlocking positions and cooperable with said control element so that adjustment of said sear to said locking position while said control element is in a starting position for said firing stroke will lock said control element in said position, said sear having a surface complementary to and cooperable with said arcuate edge portion of said control element so as to secure said sear against movement from its unlocking to its locking position after said control element has moved out of said starting position.

7. The combination set forth in claim 6 and further comprising a cocking lever rotatably mounted on said support and cooperable with said actuating element so as to move the latter from an uncocked to a cocked position by movement of said cocking lever from a released to a tensioning position, and means including a stop element nonrotatably secured to said sear and a complementary stop element connected with said cocking lever, for preventing movement of said cocking lever from said released to said tensioning position while said sear is in its unlocking position.

8. The combination set forth in claim 7, wherein said arcuate edge portion of said control element and said complementary surface portion of said sear are arranged so as to overlap each other and thereby secure said sear in its unlocking position against rotation relative to said support in either direction after said control element has been moved out of its starting position.

9. A gun firing control device for multiple gun control comprising a support; a plurality of gun trigger actuating mechanisms mounted on said support; each of said trigger actuating mechanisms having a gun trigger control element pivotally mounted on said support, a spring biased power transmitting means operatively interposed between said support and said control element for sequentially imparting a firing stroke and a return stroke in rotatively opposite directions to said control element when said transmitting means moves from a biased to an unbiased position, a cocking lever operatively associated with said transmitting means for cocking said transmitting means to a biased position, and a sear mounted for adjustment between locking and unlocking positions on said support in cooperative relation with said control element so as to prevent a firing stroke of the latter while in a locking position; and a common release means for simultaneously adjusting all of the sears for each trigger actuating mechanism to said unlocking position.

10. The combination set forth in claim 9 wherein each of said gun trigger control elements has an arcuate edge portion concentric with its pivot axis and each of said sears has a surface complementary to and cooperable with said arcuate edge portion preventing movement of said sear from an unlocking to a locking position until said control element is in its starting position for its firing stroke.
